Application May 1, 1936, Serial No. 77,366

8 Claims. (Cl. 45—2)

This invention relates to a tilting front for a file drawer.

The invention comprehends the construction of furniture, such as a filing cabinet having a drawer or a plurality of drawers provided with a tilting front adapted for movement into tilted position when the drawer is withdrawn and having mechanism operated during movement of the drawer into the cabinet for moving the front from tilted position to an upright position to close the drawer opening in the cabinet.

The invention provides a mechanism for moving the drawer front from tilted to upright position that is progressively operated with the progressive movement of the drawer from its withdrawn position to its housed position in the cabinet and secures an unusual ease of operation of the drawer front progressively with the movement of the drawer during its operation.

The invention further comprehends improvements in the construction of the front end portion of the drawer and the mounting of the tiltable front on the front end so that its tilting may be limited, and the mounting structure for the drawer front constructed to cooperate with the front end of the drawer to prevent sagging of the drawer structure in its normal use, and provide for the cooperation of the front operating mechanism in securing movement of the drawer front to an upright position during the closing movement of the drawer into the cabinet.

The invention also comprehends the provision of a tilttable drawer front formed of fire-resistant material having its marginal portion formed for sealing cooperation in the upright position with complementary sealing portions on the insulated filing cabinet, and with drawer front operating mechanism mounted within the insulated compartment in the cabinet operable to move the insulated drawer front from a tilted position to the upright position to align the sealing means on the drawer front with the complementary sealing means on the cabinet for sealing the contents of the drawer and the compartment against external heat in the closed position of the drawer.

In the drawings:

Fig. 1 is a vertical longitudinal cross section through a cabinet constructed in accordance with the invention, showing the drawer in elevation with portions of the drawer front broken away and shown in section, the drawer being in its extended position out of the cabinet.

Fig. 2 is a horizontal cross section through a cabinet showing the drawer in extended position as illustrated in Fig. 1, the drawer being shown in elevation and portions being broken away to illustrate some of the details of construction.

Fig. 3 is a view similar to Fig. 1 with the

drawer shown in housed position and the drawer front in closed position.

Fig. 4 shows a drawer constructed in accordance with the invention in perspective, with the drawer front in tilted position.

Fig. 5 shows the cam member carried by the cabinet in perspective.

Fig. 6 shows a lock mechanism in perspective.

It is to be understood that this invention is applicable to filing cabinets of all kinds as well as other types of furniture using drawers, where it is desirable to have the drawer front move into a forwardly extending position when the drawer is withdrawn from its casing. For the purpose of illustration the invention is shown as being applied to a heat insulated file cabinet comprising a casing 1 having an inner fire-resistant lining 2 formed to provide a drawer compartment for receiving and housing a drawer 3 in the compartment. The forward end of the file cabinet 20 is formed with sealing means in the form of projections 4 and grooves 5 surrounding the opening into the compartment. The drawings illustrate a fragment of a filing cabinet sufficient to show one drawer compartment and one drawer, 25 and it is to be understood that the invention may be used on cabinets or other pieces of furniture having either a single drawer or multiple drawers. The drawer compartments may be independent of one another and separated by partitions as indicated in the drawings or any other desired form of construction may be used.

Drawer guides 6 having drawer and casing carried parts of conventional design may be used for mounting drawer 3 for free movement into and out of the compartment in the casing. The drawer guides are constructed to support the drawer in its withdrawn or extended position out of the casing as shown in Figs. 1 and 2 in a manner well known in the art. Drawer guides 6 may 35 be mounted in the cabinet in the manner shown in the patent to Wolters 1,904,912, patented April 18, 1933, or in any other appropriate manner depending upon the type of cabinet construction with which the invention is associated.

The drawer 3 has side walls 7 and bottom wall 8 provided with a central channel 9 of the usual form to receive the tabs on the lower end of guide cards and increase the rigidity of the drawer. Channel 9 is formed by offsetting the 50 central longitudinal portion of the sheet metal bottom of the drawer downwardly.

At the front end a frame member 10 has a central portion 11 engaging the upper face of drawer bottom 8 along the front margin and upwardly 55 extending portions 12 at opposite ends of portion 11 engaging the inside front marginal portion of side walls 7 throughout the lower portion of the side walls. The frame member is formed from a single strip of material and the opposite ends 60

12' are offset from upwardly extending portions 12 outwardly to extend through slots 13 in the forward edge of side walls 7 and engage the outer side of the forward edges of side walls 7 5 along the upper portions thereof as clearly shown in Fig. 4.

Hinge plates 14 are formed with offset central portions 15 to provide the plates with substantial 10 rigidity and have the forward edges formed with cylindrical portions to receive a hinge pin carrying hinge plate 16 on tiltable drawer front 17 to hinge the front on the drawer. Hinge plates 14 are mounted on the forward edge of drawer bottom 8 at opposite sides of channel 9. Hinge plates 15 14 and frame member 10 are spot welded, or secured in some other suitable manner, permanently to the sheet metal bottom and sides of the drawer and cooperate to prevent sagging and distortion of the front portion of the drawer and 20 carry the load imposed on the drawer by its contents including tiltable front 17.

Tiltable front 17 has a sheet metal outer covering 18 and an inner lining of insulating material 19. Sealing means including projections 25 20 and grooves 21 is provided around the marginal portions of drawer front 17 complementary to the sealing means on the cabinet, so that when the drawer front is in the closed upright position as shown in Fig. 3 the sealing means will cooperate to effectively seal the joints between the drawer front and the cabinet and exclude external heat and fire from the compartment in the cabinet to preserve the contents against destruction. A handle 22 is provided on the drawer front 17 in the usual manner so that the drawer may be manually moved on the drawer guides 6 into the outer position shown in Fig. 1 or inner position shown in Fig. 3.

Brackets 23 are mounted on opposite sides of 40 drawer front 17 and extend rearwardly from the drawer front in substantially perpendicular relation. The front portions of the brackets where they are secured to the drawer front are offset from the remaining portions as clearly shown in 45 the drawings, while the rear edges of the brackets terminate in angular relation to the front edges. The rear ends of the brackets are formed with laterally extending stop flanges 24. Stop flanges 24 engage the rear side edges of the upper ends 50 12' of frame member 10 and limit the forwardly extending or tilting movement of drawer front 17 on its hinged mounting on the drawer, as well as support the drawer front in its forwardly extending position. Brackets 23 are held in sliding engagement with the upper ends 12' of frame member 10, by means of arcuate slots 25 formed in the brackets and guide pins 26 extending through slots 25 having heads at the outer ends, while the inner ends are mounted on the lower end portions 12' of frame member 10.

A lever mounting plate 27 is mounted on one side wall 7 of the drawer near the rear end and has an actuating or operating lever 28 pivotally secured thereto at 29 intermediate its ends. The 65 upper end of lever 28 is provided with a roller 30 while the opposite end has one end of a link 31 pivotally connected thereto with the opposite end pivotally connected at 32 to one of the bracket members 23 as clearly shown in Fig. 4. The 70 lever 28 and link 31 extend outside of the drawer along one side wall 7.

A cam member 33 is mounted in the compartment in the casing and may be suitably formed of a plate secured to a side wall of the casing. 75 This cam plate has an angular edge portion pro-

vided with an angle member 34 having a laterally extending inclined track 35. The cam plate and track portion 35 is of a length preferably extending throughout the major portion of the length of the compartment in the cabinet. Track 35 has a horizontal rear end portion 36. This structure of cam member 33 providing track portion 35 with horizontal portion 36 has roller 30 on lever 28 in rolling contact thereon for rotating lever 28 on its pivot 29.

Lever 28 and cam member 33 are constructed and arranged when the drawer is in the closed position in Fig. 3 to have roller 30 engage on horizontal track portion 36 at the rear end of the cam member. This track portion 36 will hold 15 the upper end of the lever at one extremity of its pivotal movement to operate link 31 to move and hold drawer front 17 in an upright position with the sealing means on the drawer front interengaged in cooperative sealing relation with the 20 sealing means on the front of the cabinet.

When it is desired to open the drawer it may be manually withdrawn from its compartment in the usual manner by pulling upon handle 22. As the drawer moves toward its position out of the 25 cabinet as shown in Fig. 1, roller 30 will ride along horizontal portion 36 during the first portion of the movement of the drawer, while sealing grooves and projections on the cabinet and drawer front are disengaged from one another. 30 Then, roller 30 begins to ride upwardly along inclined track portion 35 and as it rides upwardly lever 28 rotates on its pivot and allows link 29 to move forwardly whereupon drawer front 17 begins to tilt from the upright position forwardly 35 about its hinge on the drawer. As the drawer progresses outwardly from its compartment, this tilting of the drawer front progresses with the movement of the drawer so that the drawer front will reach its forward and downward limit of 40 tilting movement as the drawer reaches its outer limit of movement out of the compartment in the cabinet. The progression of tilting of the drawer front is therefore approximately the same or proportional to the progression of the drawer 45 in operation between its limits of movement. It is found that this progressive operation of the drawer and drawer front in substantially equal ratio provides for smooth operation of the drawer and the front between the outer and inner positions of the drawer relative to the casing or cabinet. 50

As the drawer is moved inwardly into the casing, roller 30 rides on inclined cam track 35. As the movement of the drawer progresses into 55 the cabinet tiltable front 17 is moved progressively toward the vertical or upright position on the drawer until it reaches the upright position shortly before the drawer reaches its rear limit of movement in the cabinet.

The purpose of having the drawer front reach the upright position before the drawer is moved entirely into the cabinet is for the purpose of positioning the drawer front so the sealing projections and grooves on the front of the cabinet and the margins of the drawer front will be properly aligned for interengagement with one another. Then, as the drawer moves into its fully closed position the sealing means is effectively interengaged and the drawer front is positively retained in the upright position by lever 28 and link 31 operating as above described.

With the drawer front tiltable forwardly as illustrated and described, it will be appreciated that card index panels housed in the drawer, or 75

guides and folders for correspondence, that are contained in the drawer may be readily manipulated so that the upper ends can be swung forwardly to provide free and ready access to the cards or contents of the folders. It will also be understood that the file panels for index cards or guides and folders for correspondence may be left in the forwardly inclined position supported by the drawer front when it is desired to close the drawer, because the closing movement of the drawer in raising the drawer front to the upright position will move the files in the drawer to the vertical position.

It will be noted that the hinge axis for the drawer front is in a plane approximately at the rear face of the drawer front so that with an insulated drawer front of the character shown in the drawings having a substantial weight, the drawer front will readily swing forwardly into its tilted position under the guidance of lever 28 and cam member 33 until flanges 24 engage with the upper ends of frame member 10.

This provides a cooperation with the drawer and the lever mechanism including the lever 28 and link 31 to obtain free movement of the drawer and the drawer front. The closing of the drawer and elevation of the drawer front into upright position through use of the lever means shown provides sufficient leverage so the weight of the drawer front does not provide sufficient resistance to the closing of the drawer to materially impede the closing operation.

It is to be understood that cam member 33 may have its lower edge extended and turned inwardly or provided with another angle member similar to member 34 in spaced parallel relation to member 34 and below it so that roller 30 may be held in substantial engagement with the track portion 35 and more positive operation of the lever on its pivot thereby obtained. This additional structure is not illustrated in the drawings because it is believed to be sufficiently obvious from Fig. 5 as to how it may be carried out as to be unnecessary of illustration.

The cabinet is provided with a suitable latching or locking mechanism for retaining the drawers in closed position. A suitable drawer latch mechanism is mounted on the drawer front 17 having an operating lever 40 mounted adjacent to handle 22 and projecting from the front face of drawer front 17 as shown in Fig. 1. Handle 40 is pivotally mounted on the drawer front and operates a suitable lever mechanism for retracting a spring projected latch bolt 41 from engagement in a keeper indicated at 42 in Fig. 2 formed in the front portion of the cabinet.

The latch bolt 41 is shown at the bottom of drawer front 17, although it may be applied to the top portion with the keeper at the top of the compartment in the cabinet. Latch bolt 41 has a beveled face so it will be cammed into front 17 as the drawer reaches the closed position when it will then drop into keeper 42. The mechanism operated by lever 40 for operating latch bolt 41 may be any conventional form of drawer latch mechanism well known in the art in view of which further illustration and description is believed to be unnecessary.

Another latching or locking mechanism is also used for retaining the drawer in closed position. This locking mechanism includes a drawer carried member 42 shown in dotted lines in Figs. 1 and 4 formed with a projection 43 adapted to be engaged when the drawer is in closed position by catch 44 pivotally mounted on bracket 45 and

spring pressed into its normal operative position by a coil spring 46 mounted on arcuate guide projection 47 carried by catch 44. The forwardly projecting end of catch 44 is formed to provide a cam face 48 so that in the closing movement of a drawer projection 43 will engage cam face 48 and move the latch 44 about its pivot until projection 43 engages in recess 49 of the latch. When projection 43 engages in recess 49 of the latch, spring 46 will project the latch into its normal position as shown in Fig. 1 and effectively lock the drawer in closed position in the cabinet. The pivotal mounting of the latch with the spring 46 operating to retain it in normal position, allows the latch to move on its pivot under the operation of projection 43 and when the latch is set in the locking position and the drawer is open, it will not interfere with the closing of the drawer.

Bracket 45 is mounted on a locking bar 50 slidably supported by channel member 51 mounted on the side wall of the casing and imbedded in the insulating lining 2. Retaining strip 52 mounted on channel bar 51 serves to retain locking bar 50 in sliding engagement in the channel bar. Channel bar 51 and locking bar 50 are provided to extend from the top portion to the bottom portion of the cabinet where it may contain more than one drawer, while a bracket 45 with the catch 44 is provided for each drawer and is mounted in the same relative position in each drawer compartment as that shown in Fig. 1. In this way, locking bar 50 will carry a latch for locking each drawer in closed position.

Locking bar 50 is shown in the inoperative position in Fig. 1 so that when any drawer in the cabinet is closed, projection 43 will be below catch 44 and will not be engaged. By moving locking bar 50 downwardly, catch 44 will be placed in operative position to engage projection 43 and retain it in recess 49. This is accomplished by having a lever 53 carried by shaft 54 rotatably mounted in a supporting bracket 55 shown in dotted lines in Fig. 2 and mounted in the side wall of the cabinet in a recess provided in insulating lining 2.

The free end of lever 53 is provided with a pin 56 engaging in a slot 57 in bar 50. A lever 58 is mounted on the opposite end of shaft 54 and has an operating link 59 pivotally connected with the free end thereof. The opposite end of operating link 59 is slidably supported in guide bracket 60 mounted in the side wall of the cabinet and is attached to a key controlled combination lock 61 slidably mounted in the extensions 62 on guide bracket 60. This lock has a laterally extending lock pin 63 that is projected by the key operated mechanism to engage in notch 64 of extension 62 on guide bracket 60 in the locked position of the parts.

In the locked position of the parts, lock member 61 is moved to its rearmost position in guide brackets 60 so that pin 63 will engage in notch 64 in extension 62. This moves operating link 59 rearwardly or to the left as shown in Figs. 1 and 6 of the drawings and rotates arm 58 in a clockwise direction as shown in Fig. 6. This rotation of arm 58 rotates shaft 54 and lever 53 and moves lock bar 50 downwardly in its guide channel 51. The downward movement of lock bar 50 by this operation positions locking latch 44 in line with projection 43 on the drawer carried member 42 so that when the drawer is closed projection 43 will engage in notch 49 as above described and the drawer will be retained in locked position in the cabinet. When the drawer is

locked in the cabinet by latch 44 the sealing grooves on the drawer front will operatively engage the sealing means on the cabinet and effi-
ciently retain the drawer in closed position. By
means of locking latch 44 and its associated locking or latching mechanism the drawer front is
also retained in the vertical position to hold the
sealing means in operative position through the
medium of cam member 33 and lever 28 since
10 these parts operatively engage in all positions
of the drawer in operation in and out of the
cabinet.

By operation of the key operated mechanism,
of conventional form contained in lock member
15 61, locking pin 63 may be withdrawn from notch
64 and spring 65 surrounding operating link 59
between the rear end of guide bracket 60 and
lock member 61 will operate to project lock
member 61 outwardly or forwardly in the bracket
20 and move levers 53 and 58 in a counter-clockwise
direction to raise lock bar 50 upwardly in its
guide channel 51 and elevate catch 44 above
projection 43 on drawer carried member 42.

In this way latch 44 will be moved out of en-
25 gagement with projection 43 and the drawer or
drawers in the cabinet controlled by this latching
mechanism will then be operative so they can be
moved to open position. In this condition of the
parts the drawer front latch device including the
30 handle 40 and latch pawl 41 will be operative to
normally hold the drawer in closed position and
provide for individual operation of any one of
a series of drawers to open position while those
not being used are retained by the latch on the
35 drawer front, in closed position, in the manner
above described. It is to be understood that in
the use of the term "latching means" in referring
to a device for holding the drawer in closed position
40 that either the latching device carried by
the drawer front or the locking device carried
by the cabinet as above described or an equivalent
mechanism thereto is contemplated by this
terminology when used in the claims.

What is claimed is:

45 1. A filing cabinet, comprising a casing, a
drawer mounted for movement into and out of
said casing, a tilttable front hinged on the front
edge of said drawer movable between upright and
tilted positions, and means on the drawer and
50 casing continuously and automatically operable
in the movement of said drawer in and out of
said casing for moving said front between said
upright and tilted positions at the opposite limits
of movement of said drawer.

55 2. A filing cabinet, comprising a casing, a
drawer mounted for movement into and out of
said casing, a tilttable front hingedly mounted on
the front edge of said drawer movable between
upright and tilted positions, linkage mechanism
60 on the drawer independent of the hinge and con-
nected to said front, and cam means on the casing
for continuously operating said linkage mech-
anism to move said front from said tilted position
65 to said upright position when the drawer is
moved from open to closed position in the cab-
inet.

3. A filing cabinet, comprising a casing, a
drawer mounted for movement into and out of
said casing, a tilttable front hinged along one
70 edge to said drawer movable between upright

and tilted positions, and means operated during
the movement of the drawer for continuously
moving said front progressively with the drawer
into upright position when the drawer is in the
casing from the tilted position with the drawer
out of said casing. 5

4. A filing cabinet, comprising a casing, a
drawer mounted for movement into and out of
said casing, a tilttable front hinged at the lower
edge to said drawer movable between upright
and tilted positions, drawer-carried means for
moving said front, and means on parts carried
by said casing, relative to which said drawer is
movable, formed for cooperation with said
10 drawer-carried means for operating said drawer-
carried means to continuously move said front
from the tilted position to the upright position
as the drawer progresses in its movement from
its outermost position to a position in the casing.
15

5. A filing cabinet, comprising a casing having
a front opening, a drawer mounted for movement
into and out of said casing through said front
opening, a tilttable front hinged along the lower
edge on said drawer movable between upright
20 and tilted positions, said front fitting and forming
a closure for said front opening in the casing
in upright position with the drawer in the casing,
and means for moving said front from tilted posi-
25 tion when the drawer is out of the casing pro-
gressively with the travel of the drawer to up-
right position closing the opening in said casing
when the drawer is in the casing. 30

6. A filing cabinet, comprising a casing, a
drawer mounted for movement into and out of
said casing, a tilttable front on said drawer, an
actuating lever pivoted on said drawer, a link
35 pivotally connected to said lever and front, and
a cam on said casing for engaging and actuating
the lever during the full cycle of movement
of the drawer to progressively move said front
40 from tilting to upright position as the drawer is
moved into said casing.

7. A filing cabinet, comprising a casing, a
drawer mounted for movement into and out of
said casing, a tilttable front on said drawer, a
45 bracket mounted on said front, an actuating lever
pivoted on said drawer, a link connecting the
bracket and lever, and means on the casing for
continuously operating said lever as the drawer
is moved from its outer limit of movement to its
50 inner limit of movement in said casing to raise
said front from tilted to upright position.
55

8. A filing cabinet, comprising a casing having
a lining of fire resistant material, a drawer
mounted for movement into and out of said cas-
ing, a drawer front having fire resistant material
forming a part thereof hinged at its lower rear
edge portion to the front edge of said drawer and
movable on the hinge between upright and for-
wardly extending positions, and means continu-
ously and automatically operable in the move-
ment of said drawer in and out of said casing for
moving said front between said upright and tilted
positions at the opposite limits of movement of
said drawer, the weight of the fire resistant
material in said front being in advance of said
hinge cooperating with said means to assist in
moving said drawer in the opening movement
thereof toward the open position. 65

GEORGE E. WATKINS. 70
